AUTOMOBILE SHADE

Filed March 24, 1928

Inventor
Daniel F. Fitzgerald
by James R. Hodder
attorney

UNITED STATES PATENT OFFICE.

DANIEL F. FITZGERALD, OF BOSTON, MASSACHUSETTS.

AUTOMOBILE SHADE.

Application filed March 24, 1928. Serial No. 264,552.

My present invention relates to shades or awnings, and more particularly to a collapsible shade primarily intended for use on automobiles or other vehicles.

5 An important object of the present invention is to provide a shade which will be compact, neat in appearance, and efficient.

A further object is to provide such a shade which will be economical to manufacture, 10 and simple to install and remove.

Another object is to provide an automobile shade which will be easily operated, either to open or closed position, in an instant's time.

15 A still further object is to provide means, automatically operable, to hold said shade in open or closed position by the simple operation of opening or closing said shade.

A further object consists in providing a 20 framework, comprising a pair of spring-metal frame members, one of said frames being adapted to be sprung into place and fixed in a window frame, means being provided on said frame to prevent movement 25 of said fixed frame away from the window, and means also being provided on said fixed frame to assist in holding said fixed frame in its position in the window frame.

A further feature resides in the provision 30 of means to limit the movement of the movable frame toward and from the fixed frame.

In carrying out my present invention I utilize a pair of spring-metal frame members, pivotally connected, one of said members adapted to be fixed in a window frame, and the other member adapted to move toward and from said fixed frame. Interposed between these two frame members, adjacent to their pivotal connection, is a 40 plate, two of these plates being preferably utilized, one at each end of the frame members. This plate carries lugs to limit the movement of the movable frame toward and from the fixed frame, and also carries a lug, 45 cooperating with another lug on the fixed frame, to hold the fixed frame in position and prevent its accidental removal from the window frame. In this plate is provided a pair of recesses, one recess alined with the 50 fixed frame member, and the other recess in a position to be alined with the movable frame member when it is in open position. Carried by the movable frame is a spring- 55 pressed plunger, adapted to engage, in either open or closed position, with one of said

recesses to hold said movable frame in open or closed position.

Carried by each side of the fixed frame, is a spring-pressed plunger, preferably rubber-tipped, operating through a recess in the 60 side of said fixed frame member, to engage the side of the window frame and assist in holding said fixed frame in its position in the window frame.

My device, when installed, will not interfere in any way with the raising or lowering of the windows, or the opening or closing of the doors.

I believe that my device, as above briefly described, is novel, and I have therefore 70 claimed the same broadly in the present application.

The above and further features of the invention, details of construction, advantages and combinations, will be hereinafter more 75 fully pointed out and claimed.

Referring to the drawings, illustrating a preferred embodiment of my invention,

Fig. 1 is a perspective view of the forward portion of an automobile, illustrating 80 my novel shade in position in one of the windows;

Fig. 2 is a plan section through the door with the shade in place;

Fig. 3 is a cross-sectional view on the line 85 3-3 of Fig. 2;

Fig. 4 is a fragmentary front elevation of the shade;

Fig. 5 is a cross-sectional view on the line 90 5-5 of Fig. 3; and

Fig. 6 is a perspective view of the corner holding plate interposed between the frame members.

Referring now to the drawings for a particular description of my invention, 1 designates generally the window frame of an automobile 2. 3 designates a window glass and 4 the usual felt strip or lining interposed between the glass 3 and the frame 1. My present novel shade or awning comprises 95 100 a frame member 5, the sides 6 thereof being adapted to bear against the sides of the frame 1. A plunger 7, preferably rubber-covered, is connected to a flat spring 8 riveted to the side 6 at 9, the spring 8 pressing 105 the plunger 7 through an aperture in the side 6 against the frame 1, thus assisting in holding the frame in position. The frame 5 is preferably of flexible or spring metal, and is adapted to be sprung into position in 110

the frame 1, the lugs 10 and 11 being positioned between the felt 4 and frame 1 to prevent movement of the frame 5 away from the frame 1. This frame 5 is designated 5 herein as a "fixed frame". The lugs 10 are shaped to partially enclose the sides 6 and but a single rivet 12 is required to hold them rigidly in place.

Pivottally mounted on the arms 6 of the 10 fixed frame, by means of a rivet or pivot pin 13, is a frame 14, movable relatively with the fixed frame 5, and preferably also of spring metal. Interposed between the arms 6 of the fixed frame, and the movable 15 frame 14, is a plate 15, held against movement on the arm 6 by the rivet 13 and a second rivet 16. The lug 11 is preferably integral with this plate 15. It will be understood that there are two of these plates 15, 20 one at each union between the fixed frame 5 and the movable frame 14, but a description of one will suffice for both. The plate 15 has a pair of smaller lugs 17 and 18, the lug 17 being adapted to limit the opening movement of the movable frame 14 and the lug 18 being adapted to limit the closing movement of said movable frame.

The plate 15 also has therein apertures or recesses 19, one of said apertures being 30 alined with the fixed arms 6, and the other of said apertures being alined with the movable frame 14 when the same is in open position, as illustrated in Fig. 3. Carried by the frame 14, and held at one end by the rivet 13, is a flat spring plate 20 having secured thereto a plunger 21 extending through an aperture in the frame 14 and automatically engaging, when in open or closed position, the recesses 19, to hold said movable frame in either open or closed position, and preventing accidental opening of said frame due to vibration, shocks or the like. The end of the plunger 21 which engages the recesses 19 is rounded, so that on suitable 45 pressure being exerted against the movable frame, the plunger 21 will be raised against the tension of the spring until it is again alined with a recess 19, whereupon it will engage said recess 19 and again exert its holding force or tension therein.

Carried by the frames 5 and 14 is a shade or awning 22, of any desired material, color or quality.

When the shade is in the position illustrated in Fig. 1, and it is desired to close or raise the same, an upward movement on the frame 14 will free the plungers 21 from the recesses 19, and will move the frame inward until it is nested within the fixed frame 5, 60 whereupon the plungers 21 will engage the recesses 19 in the plate 15 which are alined with the fixed frame and be seated therein, holding the awning or shade in closed position until it is again desired to open the 65 same.

From an inspection of Fig. 2 it will be apparent that my novel device will not interfere in the slightest with the raising or lowering of the glass 3, and from an inspection of Fig. 1 it will be seen that the said device will not interfere with the opening or closing of the doors.

My present device is neat, attractive in appearance, inexpensive, easy to install and remove, and presents many advantages.

While I have necessarily described my present invention somewhat in detail, it will be appreciated that I may vary the size, shape and arrangement of parts within reasonably wide limits without departing from the spirit of the invention.

My invention is further described and defined in the form of claims as follows:

1. A device of the kind described, comprising a fixed spring-metal frame adapted to be sprung into position in a window frame, a second spring-metal frame movable relatively with the first metal frame, means to limit the movement of the movable frame toward and from the fixed frame, means to hold said movable frame in open or closed position, and spring means carried by said fixed frame to engage said window frame and further hold said fixed frame in position therein.

2. A device of the kind described, comprising a fixed spring-metal frame adapted to be sprung into position in a window frame, a second spring-metal frame movable relatively with the first metal frame, a plate 100 interposed between said frames and fixed to said fixed frame, lugs on said plate to limit the movement of said movable frame toward and from said fixed frame, said plate having a plurality of recesses therein, spring means carried by said movable frame adapted to engage said recesses to hold said movable frame in open or closed position, lugs carried by said fixed frame and said plate to prevent movement of said fixed frame away 105 from said window, and spring means carried by said fixed frame to engage said window frame and further hold said fixed frame in position therein.

3. A device of the kind described, comprising a fixed spring-metal frame adapted to be sprung into position in a window frame, a second spring-metal frame movable relatively with the first metal frame, means to limit the movement of the movable frame toward and from the fixed frame, means to hold said movable frame in open or closed position, and spring pressed plungers carried by said fixed frame to engage said window frame and further hold said fixed 125 frame in position therein.

4. A device of the kind described, comprising a fixed spring-metal frame adapted to be sprung into position in a window frame, a second spring-metal frame movable 130

relatively with the first metal frame, a plate interposed between said frames and fixed to said fixed frame, lugs on said plate to limit the movement of said movable frame 5 toward and from said fixed frame, said plate having a plurality of recesses therein, spring pressed plungers carried by said movable frame adapted to engage said recesses to hold said movable frame in open or 10 closed position, lugs carried by said fixed

frame and said plate to prevent movement of said fixed frame away from said window, and spring pressed plungers carried by said fixed frame to engage said window frame and further hold said fixed frame in position 15 therein.

In testimony whereof, I have signed my name to this specification.

DANIEL F. FITZGERALD.
